UNITED STATES PATENT OFFICE

1,985,657

SPRING OPERATED MECHANICAL TOY

Franklin J. Gustine, New Orleans, La.

Application April 27, 1934, Serial No. 722,757

1 Claim. (Cl. 46—32)

This invention relates to improvements in spring operated mechanical toys, and it consists in providing a special construction of spring operated spinning tops in which two tops are simultaneously spun by the operation of the same spring, in which one top is used as a key to wind up the spring contained in the other top; and in which the two tops are held in the position for spinning until dropped point down to the floor, or other hard surface, when both tops are not only automatically separated but also both tops are at the same time automatically spun by the operation of the spring, each spinning on its own point.

The invention relates more especially to certain improvements on my patent No. 655,621, granted August 7, 1900, and entitled Spring operated mechanical toy or analogous device.

In the arrangement shown in the prior patent, it was found difficult to construct the parts in such a way that the device was commercially practicable, without entailing prohibitive expense. In other words, toys of this kind are primarily intended for rough usage, and are intended to be used by children who know little or anything about mechanics, or of the proper care of a mechanical device.

The toy shown in the prior patent, therefore, soon got out of order and proved unsatisfactory for various reasons.

The present invention is intended to provide a cheap and rugged structure adapted to stand the rough usage to which the device is designed and which may be cheaply made and assembled.

With the foregoing and other objects in view, the invention will be more fully described hereinafter, and will be more particularly pointed out in the claim appended hereto.

In the drawing, wherein like symbols refer to like or corresponding parts throughout the several views,

Figure 1 is a detail perspective view of the upper top in spinning position.

Figure 2 is a like view of the lower top, the dotted lines showing the spring and adjacent parts.

Figure 3 is a vertical section taken through the toy showing the upper and lower tops assembled and wound and locked together ready for launching or dropping.

Figure 4 is a detail enlarged top plan view of the lower top, showing the spindle and sleeve arrangement.

Figure 5 is a detail sectional view of the lower top after spinning and with its spring relaxed.

Figure 6 is a detail side elevation of the spindle of the lower top, the dotted lines showing the sheet metal blank forming the spindle, and

Figure 7 is a detail sectional view through the upper top, showing the spindle mounting therein.

Referring now to the drawing, and first to Figure 3, the toy comprises an upper top 10 and a lower top 11. These tops are of substantially the same construction, and each comprises a pair of concave-convex sections of sheet metal or the like, which are joined together at their marginal edges by an overturned seam 12 to provide a pair of hollow bodies.

The upper top 10 carries coaxially a rigid spindle 13 which may be of any desired construction and which projects above the body of the top 10 and is suitably tapered as at 14 to insure the falling of the top with the end 14 uppermost. The lower end of the spindle 14 is provided with a tapered blunt end 15 upon which the top is adapted to spin when deposited or launched upon a flat surface, such as the floor or other hard smooth surface. The spindle 14 is provided in spaced relation to its lower end 15 with a laterally or radially extending pin 16 to provide a winding key and a locking pawl cooperating with the lower top 11 as will subsequently appear.

The lower top 11 carries, axially, a longitudinally shiftable spindle 17 having a tapered blunt end 18 upon which the lower top may spin and the spindle 17 extends above the body of the top 11 and is provided at its upper end with a shoulder 19 preferably formed by the provision of a cam surface 20 in the upper edge of the spindle 17, the latter being preferably hollow and, as shown in Figure 6, constructed of a rolled sheet metal blank cut to form. The lower end of the upper spindle 13 projects into the upper hollow end of the lower spindle 17 and the pin 16 engages the shoulder 19 for interlocking the two spindles when the upper spindle and top are turned in one direction.

The lower spindle 17 is normally held raised by a contracting coil spring 21 secured at its lower end 22 through perforations formed in the wall of the spindle 17, and at its upper end is secured to the upper wall of the lower top 11.

The spring 21, as shown in Figure 5, normally supports the spindle 17 in raised position, and also holds it yieldingly against turning in the body of the lower top.

Suitably fixed to the upper portion of the lower top 11, and about the spindle 17, is a locking sleeve 23. The sleeve 23 provides a bearing for the upper end of the spindle 17, in which the

bearing may turn and also slide. The upper edge of the sleeve 23 is provided with one or more locking shoulders 24 which are provided by recessing the upper edge of the sleeve and which face in a direction opposite to the shoulder 19 of the spindle. The shoulder 24 is adapted to receive the outer end portion of the pin 16 thereagainst after the upper top has been turned and forced downwardly to place the spring 21 under tension both torsionally and as to lengthwise stretching.

The spiral spring 21 is preferably made of steel wire and is of sufficient length to admit of the desired winding of the toy so that when the spring is released the upper and lower sections will be given the necessary turning movement to effect spinning.

In order to operate the toy, the upper spindle 13 is inserted at its lower end into the top of the lower spindle 17. The lower top 11 is grasped in one hand and the upper top is grasped in the other hand. The two tops are turned relatively in a position to engage the pin 16 of the upper spindle with the shoulder 19 of the lower spindle so that the lower spindle is turned in the lower top during the winding action.

At the same time the upper top 10 is depressed toward the lower top 11 so as to bring the pin 16 adjacent the one or more shoulders 24. The turning and downward sliding movement of the spindle 17 not only stretches the spiral spring 21, but also places the same under torsional strain, so that there is a tendency for the spindle 17 to turn backwardly to normal position and to also rise through the lower top 11. The pin 16 is forced down into engagement with the shoulder 24 when the tops are wound sufficiently and the torsional pressure of the spring 21, acting through the spindle 17 and the shoulder 19, is sufficient to frictionally hold the pin 16 against the locking shoulder.

After the two tops have been wound together under the desired tension, they may be dropped as a unit so that the point 18 of the lower spindle 17 strikes the floor or other hard supporting surface, and the jar is sufficient, supplemented by the inertia of the lower top body 11, to dislodge the shoulder 24 from the pin 16 so that the spring 21 not only reacts against the two spindles 13 and 17 to turn them in opposite directions, but also acts to eject the upper spindle 13 out of the top of the lower spindle 17. During this ac-

tion the shoulder 19 is maintained for a sufficient period of time in pressing contact with the pin 16 so as to rapidly turn the upper spindle 13 with the upper top body 10 in a direction opposite to the turning of the locking sleeve 23 and its lower top body 11.

The result of this operation is that the tops are turned or spun in opposite directions and the upper top is ejected with sufficient force to throw it to one side of the lower top, so that the two tops are left spinning independently upon the floor or other supporting surface. The two tops 10 and 11 may be painted of different colors so as to make the device more attractive, and the contours of the two tops may also be varied if desired.

On account of cheapness in construction however, it is desirable to make the two tops identical in construction with the exception of minor changes required for the mounting of the different spindles 13 and 17 and the locking sleeve 23.

It is obvious that various changes and modifications may be made in the details of construction and design of the above specifically described embodiment of this invention without departing from the spirit thereof, such changes and modifications being restricted only by the scope of the following claim.

What is claimed is:—

A mechanical toy comprising a pair of hollow tops, a fixed spindle carried by one top with a laterally projecting pin spaced from the lower end of the spindle and said spindle being provided with reduced opposite ends, an axially movable spindle carried in the other top, said movable spindle being hollow to receive the lower end of the fixed spindle, said second spindle having a connecting shoulder in its upper end for receiving said pin for turning the spindles together when the fixed spindle is rotated in one direction, a locking sleeve carried by the second top about the spindle thereof and having a locking shoulder to receive said pin thereagainst when turned to register therewith, and a helical contractile wire spring disposed within the second top and connected at its lower end to said movable spindle and connected at its upper end to the under side of the upper portion of the second top, said spring being movable from an expanded position within the upper and lower portions of the top to a position of rest entirely within the upper portion of the top.

FRANKLIN J. GUSTINE.
